UNITED STATES PATENT OFFICE.

LAURENCE E. TOPHAM, OF SWAMPSGOTT, MASSACHUSETTS, ASSIGNOR TO UNITED SHOE MACHINERY CORPORATION, OF PATERSON, NEW JERSEY, A CORPORATION OF NEW JERSEY.

SHOE MACHINE.

Application filed December 31, 1918. Serial No. 269,076.

This invention relates to shoe machines and is herein shown as embodied in a machine for operating on shoes in which the shoe and the means for operating on the shoe are moved relatively to transfer the point of operation about the shoe and to change the relative positions of the shoe and the operating means to present the shoe properly to the operating means as the point of operation is transferred about the shoe and in which the shoe is supported in operating position in the machine and all of its movements are effected and controlled by automatically acting mechanisms.

15 The objects of the invention are to improve the construction and mode of operation of automatic shoe machines with a view of simplifying the construction and increasing the efficiency and reliability in operation of such machines.

With these objects in view a feature of the present invention contemplates the provision in an automatic machine of mechanism for actuating the jack to feed the shoe and mechanism controlled from the shoe for relatively adjusting the action of the feeding mechanism and that of the position changing mechanism for the size of the shoe to be operated upon. The said shoe controlled mechanism is preferably constructed and arranged to adjust relatively the action of the jack actuating feeding mechanism and that of the position changing mechanism for the size of the shoe upon the placing of the shoe in position in the machine to start the operation thereon. In the particular embodiment of the invention illustrated in the present application, the relative actions of the jack actuating feeding mechanism and the position changing mechanism are adjusted by adjusting said feeding mechanism, and this adjustment of the feeding mechanism is conveniently effected through the connection between the jack and said mechanism. The adjustment of the jack actuating feeding mechanism, in accordance with the size of the shoe to be operated upon, may include the timing of said mechanism relative to the position changing mechanism and certain other relative adjustments of the parts to produce the proper movement of the jack for the size of the shoe.

The jack actuating feeding mechanism may constitute the only feeding mechanism

of the machine or it may be employed in connection with feeding devices arranged directly to engage the shoe such as are embodied in shoe sewing and certain other machines. When the invention is embodied in machines provided with such feeding devices, the proper cooperative action of the jack actuating feeding mechanism, the shoe engaging feeding devices, and the position changing mechanism requires not only that the jack actuating feeding mechanism and the position changing mechanism be relatively adjusted but also that these two latter mechanisms be adjusted relatively to the shoe engaging feeding devices for the size of the shoe to be operated upon. In the present machine all of these adjustments are effected through the action of mechanism controlled from the shoe, preferably constructed and arranged to produce the proper adjustments for the size of the shoe upon the placing of the shoe in the machine in position to start the operation thereon. In the embodiment of the invention illustrated in the present application these adjustments are effected through the connection between the jack and the jack actuating feeding mechanism. In this embodiment of the invention the jack actuating feeding mechanism is operated by a cam carried by a pattern cam shaft and this mechanism is adjusted to cooperate with the shoe engaging feeding devices and the position changing mechanism is timed relatively to these devices by adjusting the speed of rotation of the pattern cam shaft.

Certain features of the invention also relate to a novel and improved shoe supporting jack mechanism which is constructed and arranged to relieve the operator of a considerable amount of the labor heretofore required in the operation of machines of this class and to enable such machines to be run by a comparatively unskilled operator. In accordance with one feature of the invention mechanism is provided which is arranged to operate automatically when thrown into operation to adjust the shoe in a predetermined position on the jack and to clamp the shoe in adjusted position. This mechanism is preferably arranged to be thrown into operation by the placing of the shoe on the jack. In accordance with another feature of the invention, mechanism

is provided which is arranged to operate automatically when thrown into operation to unclamp the shoe and to restore the parts of the jack to their initial condition ready for the reception of another shoe. This latter mechanism is preferably arranged to be actuated during the turning movement of the jack by which it is restored to starting position after the completion of an operation on the shoe. With a jack embodying these features the operator is relieved of the labor required in jacking and unjacking the shoe, the shoe is jacked and unjacked much more quickly than could be done on the jacks heretofore devised, and the locating of the shoe in a predetermined position on the jack is ensured with the exercise of practically no skill or care on the part of the operator. This novel and improved shoe supporting jack mechanism forms the subject matter of a divisional application, Serial No. 530,813, filed January 21, 1922.

The invention also comprises various other novel and improved features, constructions and combinations of parts hereinafter described and particularly pointed out in the claims the advantages of which will be readily understood and appreciated by those skilled in the art.

The features of the invention will be readily understood from the accompanying drawings illustrating the invention in its preferred form and the following detailed description of the constructions therein shown.

In the drawings Figure 1 is a view in front elevation of a machine embodying the invention; Fig. 2 is a view in side elevation of the machine looking from the right; Fig. 3 is a plan view of the machine; Fig. 4 is a view in side elevation looking from the right illustrating the sewing mechanism and the jack; Fig. 5 is a detail plan view illustrating the supporting mechanism for the jack, the mechanism for moving the jack to present the shoe properly to the operating means and certain associated parts; Fig. 6 is a view similar to Fig. 5 with certain of the parts shown in the latter figure removed to show the structure of other parts more clearly; Fig. 7 is a view illustrating the jack in front elevation and the devices at the lower end of the jack spindle in section taken substantially on the line 7—7 of Fig. 8; Fig. 8 is a detail sectional view, illustrating the devices at the lower end of the jack spindle taken substantially on the line 8—8 of Fig. 9; Fig. 9 is a sectional view taken substantially on the line 9—9 of Fig. 8; Fig. 10 is a view in vertical section of the jack; Fig. 11 is a view partly in vertical section and partly in front elevation of the jack illustrating certain of the parts in different positions from the positions in which they are shown in Fig. 10; Fig. 12 is a detail view

in vertical section illustrating a portion of the jack with certain of the parts in different positions from those in which they are shown in Figs. 10 and 11; Fig. 13 is a sectional view taken substantially on the line 13—13 of Fig. 11; Fig. 14 is a sectional view taken substantially on the line 14—14 of Fig. 11; Fig. 15 is a view in front elevation partly in section of a portion of the jack illustrating the parts in substantially the same positions as shown in Fig. 11; Fig. 16 is a view in front elevation of the portion of the jack shown in Fig. 15 with certain of the parts in different positions; Fig. 17 is a view similar to Fig. 16 illustrating certain of the parts in different positions; Fig. 18 is a view in side elevation of the portion of the jack shown in Figs. 15, 16 and 17; Fig. 19 is a sectional view taken substantially on the line 19—19 of Fig. 17; Fig. 20 is a detail view partly in side elevation and partly in section taken substantially on the line 20—20 of Fig. 10; Fig. 21 is a detail view of a portion of the jack mechanism illustrating certain of the parts in different positions from those in which they are shown in Figs. 10 and 11; Fig. 22 is a detail sectional view illustrating a dash-pot forming part of the jack mechanism; Fig. 23 is a detail view of a valve member for the dash-pot; Fig. 24 is a detail sectional view taken substantially on the line 24—24 of Fig. 2; and Fig. 25 is a detail view in side elevation illustrating a portion of the mechanism shown in Figs. 5 and 6.

The invention is illustrated in the drawings of this application as embodied in a machine the mechanism for operating upon the shoe of which consists of a sewing mechanism constructed and arranged for sewing the inseams of shoes. The invention, however, is not limited in its application to machines for sewing shoes but it may be embodied with advantage in machines for performing various operations upon shoes.

The machine illustrated in the drawings of the present application except as changed and modified in embodying the present invention in an inseam shoe sewing machine has the same general construction and organization of parts as the machines illustrated in applicant's pending applications, Serial Nos. 160,751, filed April 9, 1917, and 255,209, filed September 21, 1918. In the present machine the sewing mechanism as a whole is fixed in position and a shoe supporting jack is provided which is movably mounted in the machine to enable the shoe to be moved laterally in the direction of feed to transfer the point of operation about the shoe and laterally transversely of the direction of feed to maintain the edge of the shoe bottom in the proper lateral position with relation to the sewing mechanism and to be tipped and laterally turned to position the

shoe properly with relation to the sewing mechanism. The lateral movement of the shoe to transfer the point of operation about the shoe is imparted thereto by devices acting on the jack to impart movements to the jack to feed the shoe and by the feeding devices of the sewing mechanism which directly engage the shoe and cooperate with the jack moving feeding devices. The sewing mechanism and the mechanism for moving the jack are driven in unison during the sewing of a seam and are stopped automatically by the action of suitable stopping devices at the completion of the seam. After a seam is completed the operator disengages the shoe from the sewing mechanism and then throws into operation mechanism which acts to drive the jack moving mechanism independently of the sewing mechanism to turn the jack to its initial or starting position. When the jack reaches this position, this driving mechanism is automatically thrown out of operation.

The sewing mechanism of the machine illustrated in the drawings comprises a curved hook needle 2, a looper 4, a thread finger 6, a channel guide roll 8, and a welt guide 10. The needle, the channel guide roll and the welt guide are all mounted to reciprocate in the line of feed, and the channel guide roll is rotated in a direction to feed the work during the back feed thereof, these parts operating in timed relation to each other to feed the work continuously through the machine. The parts of the sewing mechanism are all actuated from a main driving cam shaft 12 which for the sake of convenience will be hereinafter termed the sewing cam shaft. All of the parts of the sewing mechanism briefly described above have the same construction, arrangement and mode of operation as the corresponding parts of the machine illustrated and described in application, Serial No. 260,419, filed October 31, 1918, in the name of Alfred R. Morrill, to which reference may be had for a full and complete description of the same.

The driving mechanism for the sewing cam shaft in the present machine has the same construction and mode of operation as the corresponding mechanism of the machines illustrated in applicant's pending applications, Serial Nos. 160,751 and 255,209. This mechanism comprises a driving shaft 14 upon which is mounted a fast pulley 16 and a loose pulley 18. This shaft carries a bevel gear 20 which meshes with a bevel gear 22 mounted on the upper end of a vertical counter-shaft 24. Fixed upon the counter-shaft 24 is a disk carrying the driving member 26 of a friction clutch, the driven member of which indicated at 28 is carried by a sleeve 30 loosely mounted on the counter-shaft. The sleeve 30 also carries

a spiral gear 32 meshing with a spiral gear 34 formed on a sleeve mounted on the sewing cam shaft to rotate therewith. During the sewing operation the members 26 and 28 of the friction clutch are engaged and the sewing cam shaft 12 is driven at a speed depending upon the speed of the driving shaft 14.

The jack for supporting the lasted shoe during the operation of the machine thereon comprises a heel support 34 and a toe rest 36 mounted upon the spindle 38. The movements which are imparted to the shoe during the sewing operation to place the portion of the shoe at the point of operation in the proper position with relation to the sewing mechanism as the point of operation is transferred about the shoe consists of lateral tipping movements or tipping movements about axes extending longitudinally of the shoe, longitudinal tipping movements or tipping movements about axes extending transversely of the shoe to place the marginal portion of the shoe bottom at the point of operation in the proper plane with relation to the sewing mechanism, and lateral turning movements to place the marginal line or edge of the shoe bottom at the point of operation in the proper angular position with relation to the line of feed. In addition to these tipping and turning movements the shoe is also given relatively slight vertical movements. The jack is supported in the machine so that the upper end of the jack or the end thereof adjacent the point of operation and the lower end of the jack or the end thereof remote from the point of operation are each freely movable independently of the other in directions transverse to the axis of the jack 100 spindle which constitutes the main axis of the jack, or, in the present machine, in horizontal directions. This manner of supporting the jack enables the jack and the shoe to be moved in the direction of the line of feed 105 to transfer the point of operation about the shoe and in a direction transverse to the line of feed to maintain the margin of the shoe bottom in its proper position with relation 110 to the operating means and to be tipped in any direction to bring the marginal portion of the shoe bottom at the point of operation into the proper plane. The jack is also mounted so that it may be rotated to impart lateral turning movements to the shoe to place the marginal line of the shoe bottom in the proper angular position with relation to the line of feed. The jack is also yieldingly supported vertically so that the shoe 115 may move vertically.

In the construction shown the lower end of the jack spindle is secured to a hemispherical shell or casing 40 pivoted to swing upon bearing pins 42 (see Figs 7, 8 and 9) secured in a gimbal ring 44 and having their 120

inner ends engaging in bearings in the shell. The gimbal ring 44 in turn is pivoted to swing upon bearing pins 46 mounted in the ring and having their outer ends engaging in bearings in a wheel 48. The common axis of the bearing pins 42 is preferably located substantially at right angles to the common axis of the bearing pins 46 so that the shell 40 and the jack spindle can swing in any direction about its connections with the wheel 48. The wheel 48 is mounted to rotate on a vertical hollow stud or sleeve 50 which is secured by a clamp 52 to the forward ends of supporting arms 54 (see Figs. 1, 2, 5, 6 and 22) carried by a yoke 56, a series of ball bearings being interposed between the stud 50 and the wheel 48 to enable the wheel to turn with a minimum of friction. This manner of mounting the wheel 48 enables the jack spindle to be rotated freely. The yoke 56 is provided with spaced arms 58 which embrace a second yoke 60 and the yoke 56 is pivotally connected with the yoke 60 to swing in a vertical plane by means of bearing pins 62. The yoke 60 is provided with spaced arms 64 which embrace a link frame 66 and the yoke is pivotally connected with the link frame to swing in a horizontal plane by means of bearing pins 68. The link frame 66 is pivotally connected at 70 with the end of a supporting arm 72 pivotally mounted upon a vertical shaft 74 and is pivotally connected at 76 with the end of a second supporting arm 78 pivotally mounted upon a vertical stud 80. The supporting arms 72 and 78 are of substantially the same length and the yoke 60 is pivotally connected with the link frame 66 at substantially the central point of the link frame. The yoke 60 thus is supported vertically but is free to move forwardly and rearwardly and to swing in a horizontal plane about its pivotal connection with the link frame, this connection moving substantially in a straight line perpendicular to the vertical plane of the line of feed of the machine during the forward and rearward movements of the yoke. In order to support the jack spindle and at the same time to permit it to move vertically to accommodate itself to the necessary variations in the vertical position of the shoe, a coiled spring 82 is connected at one end with an arm 84 on the yoke 60 and at its other end with an arm 86 on the yoke 56. It will be noted that the devices for supporting the jack spindles are constructed to enable the lower end of the spindle to be moved horizontally in any direction and that the connection between the lower end of the spindle and the devices for supporting the same will permit the upper end of the jack and the shoe to be moved horizontally in any direction independently of the lower end of the jack spindle.

During the sewing operation the shoe is

held positively to the machine at all times during each cycle of operations by the needle, welt guide and channel guide roll. Relatively slight vertical movements are imparted to the shoe by the action of the spring 82 on the jack and by the engagement of the channel guide roll and welt guide with the shoe, these parts acting as guides on the shoe. The required tipping movements are imparted to the shoe by devices acting on the jack spindle to move the lower end of the spindle forwardly, rearwardly and laterally of the machine in horizontal directions, and the lateral turning movements are imparted to the shoe by devices acting on the jack spindle to rotate the spindle. Because of the fact that the shoe is held at all times at the point of operation by the needle, channel guide roll and welt guide the tipping and turning movements are caused to take place about the point of operation.

In the present construction the lateral tipping movements of the shoe are produced by the forward and rearward swinging movements of the arm 72 which through the connection described between the arm and the lower end of the jack spindle impart forward and rearward movements to the lower end of the spindle, thereby tipping the jack laterally. In the construction shown, (see Figs. 1, 2, 5 and 6) a cam roll supporting lever 88 is pivoted at one end by means of a stud 90 to the arm and connected at its opposite end by a link 92 with a stationary arm 94, said arm being formed on a bracket 96 secured to the frame of the machine. The lever 88 carries a cam roll 98 which engages in a cam groove 100 in a cam disk 102 mounted on a cam shaft 104 which, for the sake of convenience, will be hereinafter termed the pattern cam shaft. By the action of the cam groove 100 on the cam roll 98 the lever 88 is actuated to impart forward and rearward swinging movements to the arm 72 and thereby to impart lateral tipping movements to the jack.

Longitudinal tipping movements are imparted to the jack and the shoe by swinging the jack supporting yokes 60 and 56 horizontally about the bearing pins 68 thereby imparting movements to the lower end of the jack spindle laterally of the machine. The required swinging movements are imparted to the jack supporting yokes (see Figs. 5 and 6) by means of a cam actuated bell crank lever 106 pivoted on the shaft 74 through a link 108 connecting the forwardly extending arm of the bell crank lever with an arm 110 on the yoke 56. A cam roll supporting lever 112 is pivoted at one end by means of a stud 114 to the laterally extending arm of the bell crank 106 and is connected at its other end by a link 116 with

a second arm 118 formed on the bracket 96. The lever 112 carries a cam roll 120 which engages in a cam groove 122 in the cam disk 102. Through the action of the cam groove 122 on the cam roll 120 the lever 112 and the bell crank lever 106 are actuated to impart through the link 108 swinging movements to the jack supporting yokes 56 and 60 about the bearing pins 68 and thereby to impart the required longitudinal tipping movements to the jack.

The lateral turning movements of the jack and the shoe are produced by imparting turning movements to the wheel 48 about the stud 50. The required turning movements are imparted to the wheel (see Figs. 1, 2, 3, 5 and 6) by means of a cable 124 passing about the wheel within a groove in the periphery thereof and secured from slipping about the wheel by means of a clamping plate 126. The part of the cable leading rearwardly from the left side of the wheel 48 extends about a pulley 128 mounted upon a stud 130 secured in the yoke 60, thence extends to the right about a pulley 132 mounted on a stud 134 secured to the arm 72 and thence about a grooved segment 136 rotatably mounted on a vertical shaft 138 and is secured at its end to the forward part of the segment. The part of the cable leading rearwardly from the right side of the wheel 48 extends about a second pulley 140 mounted on the stud 130 and thence extends to the left about a pulley 142 and over a pulley 144 both mounted on the frame of the machine. To the end of this part of the cable is secured a weight 146 which operates to keep the cable taut at all times. The required rotative movements of the wheel 48 are produced and controlled by swinging the segment 136 about the shaft 138, the swinging movement of the segment in a clockwise direction taken up on the cable 124 and producing a rotative movement of the wheel 48 in a clockwise direction, and the swinging movement of the segment in a counter-clockwise direction letting off on the cable and allowing the weight 146 to produce a rotative movement of the wheel 48 in a counter-clockwise direction.

The mechanism for producing the swinging movements of the segment 136 comprises a gear segment 148, secured to the hub of the grooved segment 136 and a cam lever 150 mounted on the vertical shaft 74 upon the forwardly extending arm of which is carried a gear segment 152 meshing with the gear segment 148. The laterally extending arm of the cam lever 150 carries a cam roll 154 engaging cam face 156 formed on a cam disk 158 mounted on the pattern cam shaft 104. The pull exerted by the weight 146 on the cable 124 tends to swing the grooved segment 136 in a counter-clockwise direction and thereby acts on the cam

lever 150 to maintain the cam roll 154 in engagement with the cam face 156 on the cam disk 158. Through the action of the cam face 156 on the cam roll 154 the cam lever 150 is actuated and controlled to impart movements to the wheel 48 in a clockwise direction and to control the movements of the wheel in a counter-clockwise direction through the connections described and thereby to impart the required lateral turning movements to the jack.

The jack illustrated in the drawings (see Figs. 10 to 21, inclusive) is constructed and arranged so that upon the placing of the shoe on the jack the shoe is automatically located in a predetermined and unvarying position lengthwise of the jack regardless of the size of the shoe placed on the jack and is then securely clamped in adjusted position, and that at the completion of the sewing operation the shoe is unclamped and the parts of the jack are restored to their initial positions ready for the application of another shoe to the jack. The shoe is gaged with relation to the jack from the forward point in the bulge in the toe portion of the upper of the shoe. The toe rest 36 is concave in cross section so that it will center the toe of the shoe relative to the last and is mounted on the upper end of an arm 160 on the jack frame. The heel support 34 consists of a last pin for insertion in the last pin hole in the last and is mounted upon a lever 162 pivoted on a stud 164 carried at the upper end of a swinging arm 166. The heel support carrying arm 166 is pivoted at its lower end to the central portion of the jack frame by means of a stud 168 so that the arm may be swung toward and from the toe rest supporting arm 160 to carry the last pin toward and from the toe rest. Before a shoe is placed on the jack the arm 166 is located in a position relatively remote from the arm 160 and upon the placing of the shoe on the last pin 34 is swung toward the arm 160 to adjust the shoe in a predetermined position longitudinally of the jack. The arm 166 is acted upon by a comparatively heavy coiled spring 170 secured at one end to a pin 172 mounted in the arm 160 and at its other end to a pin 174 mounted in the outer end of a lever 176 pivoted upon a stud 178 secured in the arm 166. Upon the hub of the lever 176 is formed a series of gear teeth 180 meshing with corresponding gear teeth 182 formed on the last pin lever 162. The opposite ends of the pin 174 are engaged in slots 177 in the arm 166 which limit the movement of the lever. When a shoe is applied to the jack the arm 166 is held substantially in the position shown in Fig. 11 relative to the arm 160 with the last pin located so that when the shoe is applied thereto the toe of the shoe will be out of engagement with the 130

toe rest as shown in said figure, the coiled spring 170 then being distended and the pin 174 held in engagement with the inner ends of the slots 177. Upon the placing of the 5 shoe on the last pin the arm 166 is released so that it is free to move under the action of the coiled spring 170. By the action of said coiled spring the arm 166 is swung toward the arm 160 thereby carrying the toe 10 of the shoe into engagement with the surface of the toe rest and sliding the same along the toe rest toward the forward end thereof. The surface of the toe rest with which the toe of the shoe is thus brought 15 into contact is inclined upwardly with relation to the arc about which the toe of the shoe is swung, so that as the toe of the shoe slides along this surface it is lifted thereby swinging the last pin lever 162 about the stud 164 relatively to the arm 166 and also 20 swinging the lever 176 about the stud 178 relatively to said arm in a direction to carry the pin 174 away from the inner ends of the slots 177. Thus when the shoe is adjusted 25 in the proper position on the jack and the swinging movement of the arm 166 ceases, the parts described will have assumed substantially the positions shown in Figure 30 10, the coiled spring 170 not only acting on the arm 166 to maintain the shoe in its adjusted position longitudinally of the jack but also through its action on the lever 176 tending to tilt the lever 162 in a direction 35 to depress the toe of the shoe and thereby clamp the shoe firmly on the jack.

In order that the shoe may be located accurately in a predetermined and definite position longitudinally of the jack, mechanism is provided for arresting the swinging movement of the heel support carrying arm 166 toward the arm 160 under the action 40 of the coiled spring 170 to adjust the shoe when the forward point of the bulge in the toe portion of the upper reaches a definite 45 predetermined position longitudinally of the jack. The mechanism for thus arresting the movement of the arm 166 comprises a bar 184 pivotally connected at one end by a stud 186 with the arm 166 and having its 50 other end arranged to pass through an opening in the toe rest supporting arm 160. The bar 184 is formed on its lower side with a series of rack teeth meshing with the teeth of a pinion 190 secured to a stud 192 55 mounted in bearings in the arm 160 (see Fig. 19). The rack bar 184 is engaged upon its upper side by a guide roll 194 which holds the same up to the pinion 190. To the forward end of the stud 192 is secured 60 a ratchet wheel 196, and a pawl 198 secured to a stud 200 mounted to turn in a bearing in the arm 160 is arranged to engage the teeth of the ratchet wheel. When the arm 166 is swung toward the arm 160 to adjust 65 the shoe longitudinally of the jack the

ratchet wheel 196 is rotated in a clockwise direction, Fig. 11, by the longitudinal movement of the rack bar 184 and the teeth of the ratchet wheel face in a direction such that the rotation of the wheel in a clockwise 70 direction will be arrested when the pawl 198 is engaged therewith. The pawl is normally held out of engagement with the ratchet wheel during the movement of the arm 166 toward the arm 160 by means of 75 a latch 202 pivoted on a stud 204 secured in the arm 160 and formed with a projection arranged to engage the tail of the pawl, as shown in Fig. 16. The latch and the pawl are both acted upon by a coiled 80 spring 206 interposed between an arm on the latch and the tail of the pawl which tends to move the latch into position to engage the pawl and also to move the pawl into engagement with the ratchet wheel 196. 85 The latch is actuated to release the pawl by means of a rod 208 mounted for longitudinal movement in guides in the arm 160 with its lower end engaging an arm on the latch. The upper end of the rod 208 is engaged by 90 a lateral projection formed on the lower end of a feeler lever 210 pivoted at 212 in a central slot in the toe rest. The upper end of the feeler lever 210 is located in position to be engaged by the bulge in the toe portion 95 of the upper of a shoe applied to the jack. As the shoe is moved forwardly on the jack by the swinging movement of the heel support carrying arm 166 under the influence of the coiled spring 170 the bulge at the toe portion 100 of the upper of the shoe engages the upper end of the feeler lever 210 thereby swinging the feeler lever on its axis and actuating the rod 208 and the latch 202 to disengage the latch from the pawl 198. Upon its release by the latch the pawl is engaged with the ratchet wheel 196 thereby arresting the rotation of the ratchet wheel and the swinging movement of the arm 166. The swinging movement of the arm 166 to adjust the 105 shoe longitudinally on the jack is thus positively arrested when the forward point in the bulge in the toe portion of the upper of the shoe reaches a predetermined position longitudinally on the jack. The shoe 110 after its adjustment in the proper predetermined position is held securely clamped on the jack by the action of the coiled spring 170 on the lever 176 as explained above. 115

The mechanism for controlling the swinging movements of the heel support carrying arm 166 comprises a toggle lever consisting of two pivotally connected links 214 and 216, one of which is pivotally connected at 120 218 with the arm 166 and the other of which 125 is pivotally connected at 220 with a lever 222 pivoted on a stud 224 carried by the central portion of the jack frame. The relative angular movement of the members of the toggle lever in a direction to straighten 130

In order to disengage the pawl 198 from the ratchet wheel 196 and to reset the pawl in position to be engaged and held by the latch 202, the rack bar 184 is formed with a projection 264 at its outer end arranged to engage a laterally projecting arm 266 formed on the pawl. As the heel support carrying arm 166 is swung from the position shown in Fig. 10 to the position shown in Fig. 11, and the bar 184 is thus moved longitudinally to the left to the position shown in the latter figure, the projection 264 on the bar engages the arm 266 on the pawl and moves the pawl from the position shown in Fig. 17 to that shown in Figs. 11 and 15. The pawl is held in the position shown in Figs. 11 and 15 until the arm 166 is released and starts to swing toward the toe rest supporting arm 160 under the influence of the coiled spring 170 when the projection 264 on the bar 184 is disengaged from the arm 266 on the pawl by the longitudinal movement of the bar to the right. The pawl is then caught by the latch and held until the latch is disengaged from the pawl by the movement of the feeler lever 210 produced by the engagement of the shoe therewith.

The devices for breaking the toggle lever 214-216 upon the placing of the shoe on the jack comprise a dog 268 pivoted at 270 upon a vertically movable block 272 and arranged to engage the laterally bent end of an arm 274 formed on the member 214 of the toggle lever. The dog 268 is acted upon by a coiled spring 276 which normally maintains the same in position to engage the end of the arm 274. The block 272 is mounted to slide on a cylindrical guide 278 formed on the lever 162 and is secured to the lower end of a rod 280 mounted for longitudinal movement in guides in said lever. The rod 280 is acted upon by a coiled spring 282 surrounding the rod within a recess 284 in the lever 162 and interposed between a washer resting on the lower face of the recess and a collar 286 mounted on the rod and held from longitudinal movement thereon by a pin 288. This pin through its engagement with the upper face of the recess 284 limits the upward movement of the rod 280. The parts are constructed and arranged so that when the rod 280 is in elevated position the upper end of the rod projects some distance above the body of the lever 162 alongside the last pin 34 and the dog 268 is located above the laterally bent end of the arm 274 in position to engage the same as shown in Fig. 12. Fig. 12 shows the condition of the parts before a shoe is applied to the jack. Upon the application of a shoe to the last pin and the seating of the last pin in the last pin hole in the last, the last engages the upper end of the rod 280 and depresses the same. During the downward movement of the rod the dog 268 engages

the end of the arm 274 and swings the same downwardly, thereby breaking the toggle lever 214-216 and allowing the arm 166 to be actuated by the spring 170 to adjust the shoe in a predetermined position on the jack 70 and to clamp the same to the jack. As the toggle lever is straightened by the turning movement imparted to the jack during the sewing of a seam, the laterally bent end of the arm 274 is swung upwardly to a position 75 outside of the lower end of the dog 268. As the arm 166 is swung away from the arm 160 by the turning movement imparted to the jack to bring the same to its initial or starting position, the end of the arm 274 80 engages the lower end of the dog 268 and swings the dog slightly against the action of the coiled spring 276 as shown in Fig. 11. Upon the removal of the shoe from the last pin the rod 280 is elevated by the action 85 of the spring 282 and the lower end of the dog 268 is swung rearwardly by the action of the coiled spring 276 over the end of the arm 274 as shown in Fig. 12. The parts of the jack are thus restored to their initial 90 positions ready for the reception of another shoe.

The movement of the heel support carrying arm 166 under the influence of the coiled spring 170 upon the release of the arm by 95 the toggle lever 214-216 if unrestrained is liable to result in breakage of certain of the parts. A dash pot mechanism is therefore provided for retarding the movement of the arm. This dash pot mechanism, as illustrated in the drawing, comprises a longitudinally movable bar 290 having rack teeth formed on its inner side meshing with the teeth of the pinion 190. The bar 290 is held up to the pinion by means of a guide 100 roll 292 engaging the outer side of the bar. To the lower end of the bar 290 is secured a sleeve 294 upon the lower end of which is formed a piston 296 fitted to reciprocate within a hollow cylinder 298 pivoted at 300 105 on the jack frame. The bore in the sleeve 294 is extended through the piston and the piston 296 is provided with a valve constructed and arranged to allow the controlling fluid to pass freely from within 110 the sleeve 294 through the piston into the cylinder below the piston, and to retard the flow of the fluid from below the piston through the same into the sleeve. The sleeve 294 is provided with open ports 302 115 to permit the fluid to pass freely from within the sleeve into the cylinder 298 above the piston.

The construction of the valve for controlling the flow of the fluid from the space 125 in the cylinder below the piston through the piston into the sleeve 294 is shown in detail in Figs. 22 and 23. As shown in these figures a bushing 304 is threaded into the bore in the piston and is formed with a cylin- 130

the toggle is limited by means of a projection 226 formed on the member 214 of the toggle lever arranged to engage an abutment or contact face on the member 216 of the lever. A toggle actuating and controlling lever 230 is pivoted on the stud 224 by the side of the lever 222 and carries an abutment screw 232 for engagement with an abutment face 234 formed on the lever 222. The levers 222 and 230 are connected by means of a coiled spring 236 which normally maintains the lever 222 in position on the stud 224 with the abutment face 234 in contact with the abutment screw 232. The lever 230 carries a bevel gear segment 238 meshing with a bevel gear 240 secured to the upper end of a shaft 242 mounted in bearings in the jack spindle 38. Upon the lower end of the shaft 242 is formed a yoke 244 (see Figs. 7, 8 and 9) which embraces a gimbal ring 246 and is pivotally connected with the ring by means of bearing pins 250 secured in the ring and engaging in bearings in the arms of the yoke. The ring 246 embraces a yoke 252 mounted on the upper end of a stud 254 mounted within and secured to the hollow stud 50 and is pivotally connected with the latter yoke by means of bearing pins 256 secured in the ring and engaging in bearings in the arms of the yoke. The common axis of the bearing pins 250 is preferably located substantially at right angles to the common axis of the bearing pins 256 as shown in Fig. 8. The shaft 242 through its connection with the stud 254 is held from rotary movement with the jack spindle but is free to swing in any direction relative to the stud in accordance with the swinging movements of the spindle. When the shoe is placed on the jack the toggle lever 214-216 is straightened and the toggle actuating and controlling lever 230 and the intermediate lever 222 are held in position on the stud 224 through the engagement of the gear segment 238 with the bevel gear 240 to maintain the heel support carrying arm 166 in a position remote from the toe rest supporting arm 160 as shown in Fig. 11 against the tension of the spring 170. Upon the placing of a shoe on the jack the toggle lever 214-216 is broken allowing the spring 170 to actuate the arm 166 to adjust the shoe in a predetermined position longitudinally of the jack and to clamp the same in position as shown in Fig. 10. The jack is turned through substantially half a revolution in the direction of the arrow α , Fig. 10, during the sewing of a seam. During this turning movement of the jack the toggle actuating and controlling lever 230 is swung on the stud 224 in the direction of the arrow applied thereto in said figure and the intermediate lever 222 is swung therewith until at the completion of the sewing of the seam the toggle lever is straightened. The jack

is turned in the opposite direction or in the direction of the arrow b , Fig. 11, through substantially half a revolution by the rotation of the correcting cam shaft independently of the sewing cam shaft to bring the jack to its initial or starting position, and the lever 230 is swung on the stud 224 in the direction of the arrow applied thereto in Fig. 11. The toggle lever 214-216 is then in a straightened condition and is moved longitudinally from the lever 230 through the lever 222 to swing the arm 166 away from the arm 160 into the position shown in said figure. The shoe is thus unclamped from the jack and may be removed from the jack merely by lifting the shoe from the last pin 34.

To take up lost motion and assist in straightening the toggle lever at the completion of the turning movement of the jack produced during the sewing of the seam a coiled spring 258 is attached at one end to the arm 166 and at its other end to a projection 260 formed on the member 214 of the toggle lever. This spring ensures the straightening of the toggle lever. The yielding connection between the intermediate lever 222 and the toggle actuating and controlling lever 230 will take care of any additional movement or overthrow of the lever 230 at the completion of the seam after the toggle lever is straightened. During such additional movement of the lever 230 the lever 222 is held stationary by the toggle lever and the lever 230 moves independently of the lever 222. Fig. 21 shows the condition of the parts resulting from such additional movement of the lever 230.

During the sewing of the seam along the shank of the shoe on the side of the shoe first sewn the jack is turned to a certain degree in the direction of the arrow b , Fig. 11. If the operator should start the machine while the toggle lever is straightened the movement of the lever 230 in the direction of the arrow, Fig. 11, which would be produced by this rotary movement of the jack would be liable to result in breakage of certain of the parts. In order to insure that the toggle lever shall be broken when this rotary movement of the jack occurs a chain 262 is attached at one end to the projection 260 on the member 214 of the toggle lever and at its other end to the lever 222. The length of this chain is such that it is drawn substantially taut when the heel support carrying arm 166 and the toggle lever are in the positions shown in Figs. 11 and 12. If the machine is started with the parts in the positions shown in these figures, the first part of the movement of the lever 222 imparted by the movement of the lever 230 in the direction of the arrow, Fig. 11, will cause the chain 262 to act on the toggle member 214 to break the toggle.

drical chamber or pocket 306 and with a central aperture 308 connecting this pocket with the bore in the piston. Within the pocket 306 is mounted a valve member 310 and a plug 312 is threaded into the pocket to hold the valve member in position. The valve member 310 consists of a plate having the general form of a cross, as clearly shown in Fig. 23. The plug 312 is adjusted in the bushing 304 so that the valve member 310 is allowed a certain amount of movement in a direction transverse to the plane of said member between the upper end of the plug and the end face of the pocket 306. The plug 312 is counterbored to form a central passage-way 314 the upper end of which is flared so that it extends beyond the inner portions of the recesses between the radially projecting arms of the valve member 310, as clearly shown in Fig. 22. The valve member 310 is constructed so that its central portion will close the opening 308 in the bushing 304 when the valve member is lifted into contact with the end face of the pocket 306, and said member is provided with a relatively small central opening 316 extending therethrough. With this construction oil is preferably used as the controlling fluid, sufficient oil being placed in the cylinder 298 to fill the space below the piston 296 when the piston is in its outermost position in the cylinder.

With this construction, when the heel support carrying arm 166 is in a position remote from the toe rest supporting arm 160 the piston 296 will occupy its uppermost position in the cylinder 298, and when the arm 166 is swung toward the arm 160 under the influence of the coiled spring 170 the rack bar 290 will be actuated to force the piston downwardly in the cylinder through the engagement of the rack bar with the pinion 190. As the piston is moved downwardly the valve member 310 will be forced upwardly into contact with the end face of the pocket 306 by the pressure of the oil below the same, so that the oil can then flow from below the valve member into the space above the bushing 304 only through the small opening 316 in the valve member. The downward movement of the piston, therefore, will be retarded so that the arm 166 will swing easily and gradually toward the arm 160. As the arm 166 is swung back in the opposite direction into the position shown in Fig. 11, the piston 296 is moved upwardly in the cylinder 298 and the valve member 310 is depressed out of engagement with the end face of the pocket 306 and into engagement with the inner end of the plug 312, as shown in Fig. 22. When the valve member is in the position shown in this latter figure the oil can pass with comparative freedom from the bore in the cylinder 298 through the opening 308, between the end face of the pocket 306 and the valve member 310, through the spaces between the radially projecting arms of the valve member and through the passage-way 314 in the plug 312 into the space in the cylinder 298 below the piston 296. The dash pot, therefore, will not furnish any considerable resistance to the movement of the arm 166 away from the arm 160 to its outer position.

The mechanism for actuating the jack to impart feeding movements to the shoe comprises a U-shaped lever 318 which may for convenience be termed the feeding lever pivoted on a stud 320 carried by a bracket 322 secured to the frame of the machine and a bar 324 connected at one end by a universal joint 326 with the forward end of the upper arm of the lever 318 and at its other end by a universal joint 328 with the forward or toe end of the jack. During the sewing operation the feeding lever 318 is swung toward the left about the stud 320 to actuate the jack to advance the marginal portion of the shoe at a substantially uniform rate past the stitch forming devices or to feed the shoe in conformity with the feeding movements normally imparted to the shoe by the shoe engaging feeding devices of the sewing mechanism. The lever 318 is actuated in this manner by means of a lever 330 the construction and arrangement of which are best shown in Figs. 1 and 3. The lever 330 has substantially a triangular shape in plan and the forward end thereof is pivotally connected at 332 with the feeding lever 318, the lever 330 engaging between the upper and lower arms of the lever 318, as shown in Fig. 1. The triangular lever 330 is pivoted at 334 between the arms of a U-shaped hanger 336 which in turn is pivoted at 338 between the arms of a lever 340 pivoted on a fixed stud 342 which may for convenience be termed the fulcrum carrying lever. During the sewing operation the lever 340 is locked in position and the triangular lever 330 is then swung about the pivotal connection 338 as a fulcrum to actuate the feeding lever 318 through certain connections from a cam carried by the pattern cam shaft. The connections for actuating the triangular lever 330 from the pattern cam shaft comprise an intermediate lever 344 pivoted on a stud 346 carried by a bracket 348 secured to the frame of the machine and a link frame 350 connecting the lever 344 with the rear end of the triangular lever 330. The intermediate lever 344 is connected by a link 352 with the laterally extending arm of a bell crank cam lever 354, (see Fig. 5) pivoted on the shaft 74. A cam roll 356 is mounted on this arm of the bell crank lever 354 and is arranged to engage a cam face 358 formed on the cam disk 158. A cable 360 is attached at one end to a cross bar connecting the two arms 139

of the feeding lever 318 and extends from said lever over a pulley 362, under a pulley 364 and over a pulley 366 all mounted on the frame of the machine and a weight 368 is suspended at the other end of the cable. The weight 368 through its action on the cable 360 tends to swing the feeding lever 318 and the forward end of the triangular lever 330 to the right and thus tends to swing the rear end of the lever 330 and the intermediate lever 344 to the left. The weight thus will act on the bell crank lever 354 to maintain the cam roll 356 constantly in contact with the cam face 358 and will eliminate lost motion or back lash between the parts of the mechanism through which the lever 318 is actuated.

The cam face 358 is preferably so formed that the triangular lever 330 is actuated to move the feeding lever 318 and through said lever to actuate the jack to feed the shoe at a substantially uniform speed past the devices for operating on the shoe. In the present machine the devices for actuating the jack to feed the shoe are constructed to impart a continuous feeding movement to the shoe. With a jack actuating feeding mechanism of the above construction, the imparting of the proper movement to the jack to feed a shoe of one size requires that a movement of greater amplitude or extent be imparted to the feeding lever 318 than is required in feeding a shoe of smaller size. To enable this mechanism for actuating the jack to feed the shoe to impart the proper feeding movement to the jack for shoes of different sizes the movement of the triangular lever 330 and the movement imparted thereby to the feeding lever 318 is adjusted to accord with the size of the shoe placed in the machine. The mounting of the fulcrum of the triangular lever 330 upon the lever 340 enables this fulcrum to be shifted forwardly or rearwardly to vary relatively the lengths of the arms of the lever 330. In changing from one size of shoe to a smaller size the fulcrum of the triangular lever 330 is shifted forwardly so that the movement of the feeding lever 318 imparted thereto by the lever 330 will be diminished, while in changing from one size to a larger size the fulcrum of the lever 330 is shifted rearwardly to increase the movement imparted by the lever 330 to the lever 318.

The fulcrum of the triangular lever 330 is located substantially in the proper position for the size of the shoe to be sewn by the placing of the shoe in the machine in correct position for the starting of the seam. At the time when the shoe is placed in the machine the fulcrum carrying lever 340 is unlocked so that it may be adjusted about its axis. When a shoe is placed in the machine in correct position for the starting of

the seam, the feeding lever 318 will be adjusted through the connections between said lever and the jack in a position depending upon the size of the shoe. The adjustment of the feeding lever 318 thus produced will effect substantially the proper adjustment of the fulcrum of the triangular lever 330. Thus in changing from one size of shoe to a smaller size the feeding lever 318 will be swung to the left upon the placing of the shoe in the machine in position to be sewn, the forward end of the triangular lever 330 will be shifted to the left with the lever 318 and the fulcrum carrying lever 340 will be swung forwardly. In a corresponding manner, in changing from one size of shoe to a larger size the feeding lever 318 will be swung to the right upon the placing of the shoe in the machine, the forward end of the triangular lever 330 will be shifted to the right therewith and the fulcrum carrying lever 340 will be swung rearwardly.

In certain machines the jack actuating feeding mechanism above described may be employed to feed the shoe without the co-operation of any other shoe feeding mechanism or may constitute the only shoe feeding mechanism of the machine, while in other machines this jack actuating feeding mechanism may be arranged to cooperate with other shoe feeding devices with which the machine is provided. In the above construction the adjustment of the fulcrum of the triangular lever 330 will time relatively the action of the jack actuating feeding mechanism and the position changing mechanism in accordance with the size of the shoe to be operated upon. With a jack actuating feeding mechanism of this construction employed as the only shoe feeding mechanism of the machine the adjustment of the fulcrum of the triangular lever 330 will adjust or time the action of the feeding mechanism relatively to the action of the position changing mechanism so that the positioning movements will be imparted to the shoe in proper timed relation to the feeding movements thereof to locate the shoe in the proper position with relation to the operating means as the point of operation is transferred about the shoe, and no other adjustment of the parts for the size of the shoe may be required. When embodied, however, in a machine provided with feeding devices directly engaging the shoe, as illustrated in the present application, the jack actuating feeding mechanism and the shoe engaging feeding devices act in an auxiliary relation to each other or cooperate to feed the shoe. In such machines it is required not only that the jack actuating feeding mechanism and the position changing mechanism be timed to operate in the proper relation to each other but also that the jack actuating feeding mechanism be

adjusted or timed to feed the shoe at the same rate that the shoe is normally fed by the shoe engaging feeding devices, and that the position changing mechanism be properly timed with relation to the shoe engaging feeding devices. In certain classes of machines it may be desirable and in others, such as shoe sewing machines, it is practically essential that the shoe engaging feeding devices operate at a constant speed regardless of the size of the shoe being operated upon. In the present embodiment of the invention the rate of movement of the feeding lever 318 is adjusted in accordance with the size of the shoe to be sewn so that said lever will actuate the jack to feed the shoe at the same speed that the shoe is normally fed by the shoe engaging feeding devices, and the position changing mechanism is timed with relation to the shoe engaging feeding devices in accordance with the size of the shoe to be sewn by adjusting the speed of the pattern cam shaft. The speed of the pattern cam shaft is adjusted automatically in accordance with the size of the shoe by the placing of the shoe in the machine in proper position for the starting of the seam through a connection between the fulcrum carrying lever 340 and the driving mechanism for the pattern cam shaft.

The mechanism for driving the pattern cam shaft and for adjusting the speed thereof in accordance with the size of the shoe to be sewn in the present embodiment of the invention has the same construction, arrangement and mode of operation as the corresponding mechanism of the machine illustrated and described in applicant's pending application, Serial No. 255,209, filed September 21, 1918. To enable the invention to be more clearly understood, however, this mechanism is briefly described in the present application. As illustrated in the drawings (see Figs. 1, 2 and 3) the pattern cam shaft is driven through a spiral gear 370 journaled on a shaft 372 and meshing with a spiral gear 374 secured to the upper end of the pattern cam shaft. The spiral gear 370 is held from movement longitudinally on the shaft 372 and the shaft is slidably mounted in bearings in sleeves 376 and 378 journaled in the frame of the machine. The sleeve 376 carries at one end a bevel gear 380 and the sleeve 378 carries at one end a bevel gear 382, these gears intermeshing with an intermediate bevel gear 384 secured to the lower end of a vertical counter-shaft 386 arranged in alignment with the counter-shaft 24 but capable of being rotated independently of said shaft. The spiral gear 370 is adapted to be clutched either to the bevel gear 380 or to the bevel gear 382, the respective bevel gears and the spiral gear being provided with inter-engageable clutch projections. The

spiral gear 370 may be shifted longitudinally to clutch the same either to the bevel gear 380 or to the bevel gear 382 by the longitudinal movement of the shaft 372 in its bearings in the sleeves 376 and 378. The shaft 372 may be shifted longitudinally by means of a lever 388 pivoted on a stud 390 and connected by a link 392 with a block 394 secured to one end of the shaft 372. To enable the lever 388 to be actuated to shift the shaft 372 and to be held in adjusted position an operating lever 396 is pivoted to an arm of the lever 388 by means of a stud 398 and carries a spring pressed latch pin 400 for engagement with any one of a series of openings 402 in a gage plate 404 formed on the frame. During the sewing operation the spiral gear 370 is clutched to the bevel gear 382 and the pattern cam shaft is then driven from the bevel gear 382 through the spiral gear 370 in a clockwise direction as indicated by the arrows in Figs. 3, 5 and 6. The spiral gear 370 is clutched to the bevel gear 380 to drive the pattern cam shaft in the reverse or in a counter-clockwise direction only for the purpose of adjusting the pattern cam shaft angularly to enable the cam disks to be removed from the shaft.

During the sewing operation the bevel gear 382 is driven to drive the pattern cam shaft in definite timed relation to the sewing cam shaft by mechanism acting to drive the sleeve 378. In the construction shown, a gear 406 is secured to the outer end of the sleeve 378 and meshes with a gear 408 secured to the inner end of a shaft 410. To the outer end of the shaft 410 is secured a second gear 412 which meshes with a gear 414 secured to the outer end of a shaft 416. To the inner end of the shaft 416 is secured the driven member 418 of a clutch, the driving member of which indicated at 420 is mounted to slide longitudinally of the shaft 416 and to rotate independently of said shaft. The clutch members are provided with inter-engaging, oppositely inclined, clutch teeth, and the driving member of the clutch is yieldingly held in engagement with the driven clutch member by a series of coiled springs not shown. The driving clutch member 420 is driven from a spiral gear 422 journaled on the shaft 416 and meshing with a spiral gear 424 formed on the lower end of a rotary sleeve 426, to the upper end of which is secured a ratchet wheel 428 through which the sleeve is driven. The ratchet wheel 428 is engaged by a series of spring pressed driving pawls 430 respectively pivoted upon oscillatory levers 432 pivotally mounted on a disk 434 secured to a counter-shaft 436. The counter-shaft 436 is journaled at its lower end in the sleeve 426 and at its upper end in a bearing 438 on the frame and is driven from the sewing

cam shaft through a spiral gear 440 secured to one end of the sewing cam shaft and an intermeshing spiral gear 442 secured to the upper end of the counter-shaft. The angular position of the pawl carrying levers 432 on their respective pivot studs is controlled by means of a non-rotating ring 444 secured to the upper end of a rock shaft 446 and having a circular groove 448 in which 5 engage rolls 450 mounted on the respective pawl carrying levers. With this construction the speed at which the ratchet wheel 428 is driven by the pawls 430 may be varied by adjusting the ring about the axis of the 10 rock shaft 446. During the sewing operation the pattern cam shaft is driven from the ratchet wheel 428 through the connections described between the ratchet wheel and the cam shaft 12. The ring 444 is adjusted to adjust the speed at which the pattern cam shaft is driven from the ratchet wheel 428 in accordance with the size of the shoe to be sewn by the placing of the shoe in the machine in position for the starting 15 of the seam. The ring 444 is adjusted upon the placing of the shoe in the machine in position to start the seam by the adjustment of the rock shaft 446 effected through an arm 452 secured to the lower end of the rock 20 shaft, and a link 454 connected at one end by a universal joint with a rearwardly extending arm on the fulcrum carrying lever 340 and at the other end by a universal joint with the arm 452. It will thus be seen that 25 the adjustment of the lever 340 produced upon the placing of the shoe in the machine in position to be sewn not only adjusts the fulcrum of the lever 330, but also adjusts the speed of the pattern cam shaft in accordance 30 with the size of the shoe. This adjustment of the speed of the pattern cam shaft times the jack actuating feeding mechanism relatively to the shoe engaging feeding devices so that the jack will be moved by said 35 mechanism to feed the shoe at the same rate that the shoe is normally fed by said devices and will also time the position changing mechanism relatively to the shoe engaging feeding devices. Shoe feeding devices which are arranged to feed the shoe through their engagement with the shoe as in the present machine will not feed the shoe at a uniform or predetermined rate at all times but will of themselves produce or permit variations in 40 the rate of feed from a constant or predetermined rate. When such variations occur the shoe and the position changing mechanism will be thrown out of their proper timed relations. The jack actuating feeding mechanism of the present machine, however, will 45 not only assist in feeding the shoe but will keep the shoe and the position changing mechanism constantly in their proper timed relations during the operation on a shoe.

60 The mechanisms for driving the various

parts of the machine illustrated in the drawings and the stopping mechanisms therefor have the same construction, arrangement and mode of operation as the driving and stopping mechanisms of the machine illustrated and described in applicant's application, Serial No. 255,209, filed September 21, 1918, to which reference may be had for a full and complete description of the same. Certain of the parts of these mechanisms 70 have been described in the foregoing description. To enable the invention to be more clearly understood, however, certain of the other parts of these mechanisms are briefly described and the operation of these 75 mechanisms is outlined in the present application. The members 26 and 28 of the main driving clutch are engaged to start the machine by means of a treadle 456, a lever 458, a treadle rod 460 connecting the treadle with 80 the lever, and connections not shown between the lever and the sleeve 30 through which the sleeve is elevated to engage the driven clutch member 28 with the driving clutch member 26 upon the depression of the 85 treadle. After the lasted shoe has been placed by the operator on the jack and has been located in a predetermined position on the jack and clamped to the jack by the automatically acting devices of the jack the 90 operator inserts the shoe in the machine with the channel guide roll 8 within the channel of the insole at the proper point for the starting of the seam, and engages the members of the main driving clutch by depressing the treadle. During the sewing operation the members 26 and 28 of the main driving clutch are held in engagement by 95 means of a latch acting on certain of the connections intermediate the lever 458, and the sleeve 30 and the machine is driven at a speed depending upon the speed of the driving shaft 14. When the sewing operation is completed, this latch is thrown out, the members of the main driving clutch are 100 disengaged, and the machine is stopped through the action of automatically acting devices. The mechanism for controlling the throwing out of the latch and the throwing 105 in of the stopping devices is actuated and controlled by a cam carried by one of the cam disks mounted on the pattern cam shaft. When the machine has been stopped at the conclusion of the sewing operation the operator manipulates the jack to disengage the 110 channel guide roll 8 from the channel of the insole and then severs the thread intermediate the thread handling devices and the shoe. Then while holding the jack with a shoe 115 disengaged from the machine, the operator throws in a clutch mechanism which connects the shaft 386 directly with the shaft 24 to drive the pattern cam shaft independently of the sewing cam shaft to bring the jack to its initial or starting position. During 120

125

130

the rotation of the pattern cam shaft the jack is turned through substantially half a revolution in a direction reverse to that in which it is turned during the sewing operation and the parts of the jack are actuated to unclamp the shoe and to place the parts in the positions shown in Fig. 11. When the pattern cam shaft has described substantially a complete revolution from the point at which it started at the beginning of the sewing operation, thereby restoring the jack to starting position, this clutch mechanism is automatically thrown out of operation.

The mechanism for connecting the shaft 386 directly with the shaft 24 to drive the pattern cam shaft independently of the sewing cam shaft to bring the jack to starting position comprises a roll or Horton clutch 462, the driving member of which is secured to the lower end of the shaft 24, and a clutch dog 464 mounted on the upper end of the shaft 386 and arranged to engage the driven member of the roll clutch. During the sewing operation the devices for controlling the engagement and disengagement of the roll clutch are held in position to maintain the roll clutch out of operation by means of a latch 466 secured to the rear end of a stud 468 mounted in a bearing in the frame to the forward end of which is secured an operating handle 470. In throwing the roll clutch into operation, the operator grasps the operating handle 470 and swings the same to the right, thereby throwing the latch 466 out of operating position. When the pattern cam shaft has described substantially a complete revolution from the point at which it started at the beginning of the sewing operation, the devices for controlling the engagement of the roll clutch are actuated to throw out the clutch through connections from a cam carried by one of the cam disks on the pattern cam shaft.

The locking mechanism for locking the lever 340 in position during the sewing operation is substantially the same as the corresponding mechanism of the machine illustrated and described in applicant's pending application referred to above. This locking mechanism comprises a rod 472 pivotally connected at its forward end with the lever 340 and engaging in a sleeve 474 pivoted on a stud 476 secured in the frame of the machine, and a pair of locking levers 478 pivoted to the sleeve upon studs 479 and formed with cam-shaped inner ends arranged to engage the rod 472. The outer ends of the locking levers 478 carry pins 480 engaging in slots formed in the opposite ends of a crossbar 482 to the central part of which is pivotally connected a sleeve 484 having a yielding connection through a coiled spring 486 with a rod 488 engaging in the sleeve. The right hand end of the rod 488 is pivotally connected with the up-

per end of a lever 490. Upon the depression of the treadle to start the machine, the lever 490 is actuated through certain of the connections intermediate the lever 458 and the sleeve 30 to swing the upper end of the lever 490 to the right and thereby move the rod 488 longitudinally to the right to actuate the locking levers 478 to lock the rod 472 in the sleeve 474. The lever 490 is held in locking position by means of a spring pressed latch pin. This latch pin is controlled through certain connections intermediate the latch 466 and the roll clutch 462 so that as the roll clutch is thrown into operation, the latch pin is actuated to release the lever 490 allowing the upper end of the lever to swing to the left to unlock the rod 472 and the lever 340. Thus when the parts of the machine have been brought to rest in positions ready for the reception of another shoe, the lever 340 is unlocked so that it may be adjusted by the placing of another shoe in the machine in position for the starting of a seam.

Having explained the nature and object of the invention, and having specifically described a machine embodying the same, what is claimed is:

1. A machine for operating on shoes having, in combination, means for operating along the bottom margin of a shoe, a shoe supporting jack, mechanism for moving the jack to feed the shoe to transfer the point of operation about the shoe, mechanism for changing the relative positions of the jack and operating means to present the shoe properly to the operating means as the point of operation is transferred about the shoe, and mechanism controlled from the shoe for adjusting the feeding mechanism in accordance with the size of the shoe to be operated upon.

2. A machine for operating on shoes having, in combination, means for operating along the bottom margin of a shoe, a shoe supporting jack, mechanism for moving the jack to feed the shoe to transfer the point of operation about the shoe, mechanism for changing the relative positions of the jack and operating means to present the shoe properly to the operating means as the point of operation is transferred about the shoe, and mechanism controlled by the placing of the shoe in position in the machine to start the operation thereon for adjusting the feeding mechanism in accordance with the size of the shoe to be operated upon.

3. A machine for operating on shoes having, in combination, means for operating along the bottom margin of a shoe, a shoe supporting jack, mechanism for feeding the shoe to transfer the point of operation about the shoe, mechanism for changing the relative positions of the jack and operating means to present the shoe properly to the

operating means as the point of operation is transferred about the shoe, and mechanism controlled from the shoe for adjusting the feeding mechanism in accordance with 5 the size of the shoe to be operated upon.

4. A machine for operating on shoes having, in combination, means for operating along the bottom margin of a shoe, a shoe supporting jack, mechanism for feeding the 10 shoe to transfer the point of operation about the shoe, mechanism for changing the relative positions of the jack and operating means to present the shoe properly to the operating means as the point of operation 15 is transferred about the shoe, and mechanism controlled by the placing of the shoe in position in the machine to start the operation thereon for adjusting the feeding mechanism in accordance with the size of 20 the shoe to be operated upon.

5. A machine for operating on shoes having, in combination, means for operating on a shoe, a shoe supporting jack, mechanism for moving the jack to feed the shoe, shoe 25 feeding mechanism arranged directly to engage the shoe, mechanism for changing the relative positions of the jack and the operating means to present the shoe properly to the operating means as the point of operation 30 is transferred about the shoe, and mechanism controlled from the shoe for relatively timing the two feeding mechanisms and the position changing mechanism in accordance with the size of the shoe to be 35 operated upon.

6. A machine for operating on shoes having, in combination, means for operating along the bottom margin of a shoe, a shoe supporting jack movable to transfer the 40 point of operation about the shoe, mechanism for changing the relative positions of the jack and operating means to present the shoe properly to the operating means as the point of operation is transferred about the shoe, means for feeding the shoe comprising 45 a cam and connections actuated from the cam for imparting feeding movements to the jack, and means controlled from the shoe for relatively adjusting the parts of said connections in accordance with the size of 50 the shoe to be operated upon.

7. A machine for operating on shoes, having, in combination, means for operating along the bottom margin of a shoe, a shoe 55 supporting jack, movable to transfer the point of operation about the shoe, means for feeding the shoe comprising a lever, a cam for moving the lever, connections between the lever and the jack for moving the jack 60 to feed the shoe, and a variable fulcrum for the lever arranged to be adjusted in accordance with the size of the shoe to be operated upon through said connections by the placing of the shoe in position in the 65 machine to start the operation thereon.

8. A machine for operating on shoes having, in combination, means for operating along the bottom margin of a shoe, a shoe supporting jack movable to transfer the point of operation about the shoe, means 70 for moving the jack to feed the shoe comprising a lever, a cam for moving the lever, a variable fulcrum for the lever, and means controlled from the shoe for adjusting the fulcrum of the lever in accordance with the 75 size of the shoe to be operated upon.

9. A machine for operating on shoes having, in combination, means for operating on a shoe, a shoe supporting jack, mechanism for moving the jack to feed the shoe, 80 shoe feeding mechanism arranged directly to engage the shoe, mechanism for changing the relative positions of the jack and the operating means to present the shoe properly to the operating means as the point of 85 operation is transferred about the shoe, and means controlled from the shoe for adjusting the action of said mechanisms as required for the size of the shoe to be operated upon.

10. A machine for operating on shoes having, in combination, means for operating on a shoe, a shoe supporting jack, mechanism for moving the jack to feed the shoe, shoe feeding mechanism arranged directly to engage the shoe and constructed to impart a constant feed movement to the shoe regardless of size, mechanism for changing the relative positions of the jack and the operating means to present the shoe properly 100 to the operating means as the point of operation is transferred about the shoe, and mechanism controlled from the shoe for adjusting and timing the jack actuating feeding mechanism and the position changing 105 mechanism with relation to each other and to the shoe engaging feeding mechanism in accordance with the size of the shoe to be operated upon.

11. A machine for operating on shoes having, in combination, means for operating on a shoe, a shoe supporting jack, mechanism for moving the jack to feed the shoe, shoe feeding mechanism arranged directly to engage the shoe, mechanism for changing the 115 relative positions of the jack and the operating means to present the shoe properly to the operating means as the point of operation is transferred about the shoe, and means controlled from the shoe for adjusting the 120 jack actuating feeding mechanism to vary the amplitude of movement imparted thereby to the jack, and for relatively timing said mechanism in accordance with the size of the 125 shoe to be operated upon.

12. A machine for operating on shoes having, in combination, means for operating on a shoe, a shoe supporting jack, mechanism for moving the jack to feed the shoe, shoe feeding mechanism arranged directly to en- 130

gage the shoe, mechanism for changing the relative positions of the jack and the operating means to present the shoe properly to the operating means as the point of operation is transferred about the shoe, and mechanism controlled from the shoe for adjusting the jack actuating feeding mechanism to vary the amplitude of movement imparted thereby to the jack, and to time the same 10 with relation to the position changing mechanism, and for adjusting the position changing mechanism to time the same with relation to the shoe engaging feeding mechanism for the size of the shoe to be operated upon.

13. A machine for operating on shoes having, in combination, means for operating on a shoe, a shoe supporting jack, mechanism for moving the jack to feed the shoe, shoe feeding devices arranged directly to engage the shoe, mechanism for changing the relative positions of the jack and the operating means to present the shoe properly to the operating means as the point of operation 25 is transferred about the shoe, a common driving cam shaft for the jack actuating feeding mechanism and the position changing mechanism, and means controlled from the shoe for adjusting the speed of said shaft in accordance with the size of the shoe to be operated upon.

14. A machine for operating on shoes having, in combination, means for operating on a shoe, a shoe supporting jack, mechanism 35 for moving the jack to feed the shoe, shoe feeding devices arranged directly to engage the shoe, mechanism for changing the relative positions of the jack and the operating means to present the shoe properly to the operating means as the point of operation is transferred about the shoe, a common driving cam shaft for the jack actuating feeding mechanism and the position changing mechanism, and means controlled from the shoe for adjusting the jack actuating feeding mechanism to vary the amplitude of movement imparted thereby to the jack and for adjusting the speed of said shaft in accordance with the size of the shoe to be operated upon.

15. A machine for operating on shoes having, in combination, means for operating along the bottom margin of a shoe, a shoe supporting jack movable to transfer the point of operation about the shoe, mechanism for moving the jack to feed the shoe comprising an actuating cam shaft and connections intermediate said shaft and the jack, shoe feeding devices arranged directly to engage the shoe, and means controlled from the shoe for adjusting said connections to vary the amplitude of movement imparted by the cam shaft to the jack and for adjusting the speed of the cam shaft to time the jack actuating feeding mechanism with relation

to the shoe engaging feeding devices for the size of the shoe to be operated upon.

16. A machine for operating on shoes having, in combination, means for operating along the bottom margin of the shoe, a shoe supporting jack movable to transfer the point of operation about the shoe, mechanism for moving the jack to feed the shoe comprising a lever, a connection intermediate the lever and the jack, a variable fulcrum for the lever, a cam shaft for actuating the lever, shoe feeding devices arranged directly to engage the shoe, and means controlled from the shoe for adjusting the fulcrum of the lever and the speed of the cam shaft for the size of the shoe to be operated upon.

17. A machine for operating on shoes having, in combination, means for operating on a shoe, a shoe supporting jack, mechanism for changing the relative positions of the jack and the operating means to present the shoe properly to the operating means as the point of operation is transferred about the shoe comprising a main actuating cam shaft, feeding devices arranged to engage directly the shoe, means for moving the jack to feed the shoe comprising a lever, a cam carried by said cam shaft for moving the lever, connections between the lever and the jack for moving the jack to impart feeding movements to the shoe, a variable fulcrum for the lever, and means controlled from the shoe for adjusting the fulcrum of the lever and the speed of the cam shaft in accordance with the size of the shoe to be operated upon.

18. A machine for operating on shoes having, in combination, means for operating on a shoe, a shoe supporting jack, mechanism for changing the relative positions of the jack and the operating means to present the shoe properly to the operating means as the point of operation is transferred about the shoe comprising a main actuating cam shaft, feeding devices arranged to engage directly the shoe, means for moving the jack to feed the shoe comprising a lever, a cam carried by said cam shaft for moving the lever, connections between the lever and the jack for moving the jack to impart feeding movements to the shoe, a hanger for supporting the lever pivotally connected therewith, a second lever supporting the hanger, a pivotal connection between the hanger and the second lever forming the fulcrum of the first lever, and devices controlled by the second lever for adjusting the speed of the cam shaft for the size of the shoe to be operated upon, the second lever being adjusted through said connections from the shoe for the size of the shoe.

19. A machine for operating on shoes having, in combination, means for operating along the bottom margin of a shoe, a shoe supporting jack movable to transfer the point of operation about the shoe, means for

- feeding the shoe comprising a lever, a cam for moving the lever, connections between the lever and the jack for moving the jack to feed the shoe, a variable fulcrum for the lever, and mechanism controlled by the placing of the shoe in position in the machine to start the operation thereon for adjusting the fulcrum of the lever in accordance with the size of the shoe to be operated upon.
20. A machine for operating on shoes having, in combination, means for operating along the bottom margin of a shoe, a shoe supporting jack movable to transfer the point of operation about the shoe, mechanism for moving the jack to feed the shoe comprising a lever, a link pivotally connected at one end with the lever and at its other end with the toe portion of the jack, and a cam for actuating the lever.
21. A machine for operating on shoes having, in combination, means for operating along the bottom margin of a shoe, a shoe supporting jack movable to transfer the point of operation about the shoe, mechanism for moving the jack to feed the shoe comprising a lever, a link pivotally connected at one end with the lever and at its other end with the toe portion of the jack, a cam for moving the lever, and a variable fulcrum for the lever adjustable in accordance with the size of the shoe to be operated upon.
22. A machine for operating on shoes having, in combination, a freely movable shoe supporting jack, means for imparting lateral movements to the jack, and devices comprising a channel guide, a welt guide and a needle arranged to engage the shoe at the point of operation and causing the lateral movements imparted to the jack to tip the shoe about said devices as a fulcrum to locate the shoe bottom at the point of operation in the proper plane.
23. A machine for operating on shoes having, in combination, means for operating on a shoe, a shoe supporting jack, mechanism for moving the jack to feed the shoe, shoe feeding mechanism arranged directly to engage the shoe, mechanism for changing the relative positions of the jack and the operating means to present the shoe properly to the operating means as the point of operation is transferred about the shoe, and means for relatively timing the two feeding mechanisms and the position changing mechanism to adapt the machine for operation on shoes of different sizes.
24. A machine for operating on shoes having, in combination, means for operating on a shoe, a shoe supporting jack, mechanism for moving the jack to feed the shoe, shoe feeding mechanism arranged directly to engage the shoe, and mechanism for changing the relative positions of the jack and the operating means to present the shoe
- properly to the operating means as the point of operation is transferred about the shoe comprising means for imparting turning and tipping movements to the shoe.
25. A machine for operating on shoes having, in combination, means for operating on a shoe, a shoe supporting jack, mechanism for moving the jack to feed the shoe, shoe feeding devices arranged directly to engage the shoe, mechanism for changing the relative positions of the jack and the operating means to present the shoe properly to the operating means as the point of operation is transferred about the shoe, a common driving cam shaft for the jack actuating feeding and position changing mechanism, and means for adjusting the speed of said shaft to adapt the machine for operation on shoes of different sizes.
26. A machine for operating on shoes having, in combination, means for operating on a shoe, a shoe supporting jack mechanism for moving the jack to feed the shoe, shoe feeding devices arranged directly to engage the shoe, mechanism for changing the relative positions of the jack and the operating means to present the shoe properly to the operating means as the point of operation is transferred about the shoe including a cam shaft, and means for adjusting the speed of said shaft to adapt the machine for operation on shoes of different sizes.
27. A machine for operating on shoes having, in combination, means for operating along the bottom margin of a shoe, a shoe supporting jack, a pattern cam and connections between the cam and the jack for moving the jack to feed the shoe to transfer the point of operation about the shoe, and means for adjusting the speed of said pattern cam to the size of the shoe operated upon.
28. A machine for operating on shoes having, in combination, means for operating along the bottom margin of a shoe, a shoe supporting jack, a pattern cam and connections between the cam and the jack for moving the jack to feed the shoe to transfer the point of operation about the shoe, said connections being adjustable for shoes of different sizes, and means for adjusting the speed of said pattern cam to the size of the shoe operated upon.
29. A machine for operating on shoes having, in combination, means for operating along the bottom margin of a shoe, a shoe supporting jack, mechanism for moving the jack to impart a continuous feeding movement to the shoe to transfer the point of operation about the shoe, and means for adjusting said mechanism to cause the point of operation to be transferred along the bottom margin of shoes of different sizes at the same speed.

30. A machine for operating on shoes having, in combination, means for operating along the bottom margin of a shoe, a shoe supporting jack, mechanism for moving the jack to feed the shoe to transfer the point of operation about the shoe, a channel guide to engage the inseam channel in contact with which the shoe is moved and which determines the position of the shoe transversely of the direction of feed, and means for moving the jack to tip the shoe about said guide as a fulcrum. 5
- 10 31. A machine for operating on shoes having, in combination, means for operating along the bottom margin of a shoe, a shoe supporting jack, a guide in proximity to the point of operation past which the shoe is moved and which determines the position of the shoe transversely of the direction of feed, a cam shaft separate from the jack, a pattern cam on the shaft, and connections between the cam and the jack for moving the jack to feed the shoe to transfer the point of operation about the shoe. 20
- 15 32. A machine for operating on shoes having, in combination, means for operating along the bottom margin of a shoe, a shoe supporting jack, mechanism for moving the jack to feed the shoe to transfer the point of operation about the shoe, a channel guide to engage the inseam channel in contact with which the shoe is moved and which determines the position of the shoe transversely of the direction of feed, and means for imparting tipping movements to the shoe to present the shoe properly to the operating means. 30
- 25 33. A machine for operating on shoes having, in combination, means for operating along the bottom margin of a shoe, a shoe supporting jack movable to transfer the point of operation about the shoe, a channel guide to engage the inseam channel in contact with which the shoe is moved and which determines the position of the shoe transversely of the direction of feed, and means for moving the jack to tip the shoe about said guide as the point of operation is transferred about the shoe. 40
- 35 34. A machine for operating on shoes having, in combination, means for operating along the bottom margin of a shoe, a shoe supporting jack movable to transfer the point of operation about the shoe, a channel guide to engage the inseam channel in contact with which the shoe is moved and which determines the position of the shoe transversely of the direction of feed, and means for imparting tipping movements to the shoe to present the shoe properly to the operating means as the point of operation is transferred about the shoe. 50
- 40 of the direction of feed, and means for imparting tipping movements to the shoe to present the shoe properly to the operating means as the point of operation is transferred about the shoe. 60
- 45 35. A machine for operating on shoes having, in combination, means for operating along the bottom margin of a shoe, a shoe supporting jack, mechanism for moving the jack to feed the shoe, mechanism for changing the relative positions of the jack and operating means to present the shoe properly to the operating means as the point of operation is transferred about the shoe, and means controlled from the shoe for relatively adjusting the action of the feeding mechanism and that of the position changing mechanism for the size of the shoe to be operated upon. 70
- 50 36. A machine for operating on shoes having, in combination, means for operating along the bottom margin of a shoe, a shoe supporting jack, mechanism for moving the jack to feed the shoe, mechanism for changing the relative positions of the jack and operating means to present the shoe properly to the operating means as the point of operation is transferred about the shoe, and mechanism controlled by the placing of the shoe in position in the machine to start the operation thereon for relatively adjusting the action of the jack actuating feeding mechanism and that of the position changing mechanism for the size of the shoe to be operated upon. 80
- 55 37. A machine for operating on shoes having, in combination, means for operating along the bottom margin of a shoe, a longitudinally movable and rotatable shoe supporting jack, a pattern cam separate from the jack and connections between the cam and the jack for moving the jack to feed the shoe to transfer the point of operation about the shoe, and means for adjusting said connections to the size of the shoe operated upon. 90
- 60 38. A machine for operating on shoes having, in combination, means for operating along the bottom margin of a shoe, a longitudinally movable and rotatable shoe supporting jack, mechanism for moving the jack to feed the shoe to transfer the point of operation about the shoe, and cams and suitable connections for imparting tipping movements to the jack to present the shoe properly to the operating means as the point of operation is transferred about the shoe. 100
